UNITED STATES PATENT OFFICE.

ABRAM T. BALDWIN, OF DETROIT, MICHIGAN; CATHERINE P. BALDWIN EXECUTRIX
OF SAID ABRAM T. BALDWIN, DECEASED.

DRAFT-GAGE.

1,352,719.

Specification of Letters Patent. Patented Sept. 14, 1920.

Application filed December 13, 1917. Serial No. 206,977.

To all whom it may concern:

Be it known that I, ABRAM T. BALDWIN, a citizen of the United States, residing in the city of Detroit, county of Wayne, State of Michigan, have invented a new and useful Draft-Gage, of which the following is a specification.

The primary object of my invention is to concentrate the draft gages or independent pressure regulators which indicate the three drafts of a boiler unit, namely, the primary draft or that for primary combustion, the pressure draft in the combustion chamber and the pressure of the gases beyond the combustion chamber and at or near the outlet from the furnace.

In general practice the pressure or draft gages which indicate the several pressures or drafts of a typical boiler-unit, have been placed either at different points upon the boiler front or at places remote from the boiler front so that it has been difficult and sometimes impossible for the average operating boilerman to see at a glance the controlling draft conditions of the boiler-unit as a whole.

In the past practice it has, moreover, been usual to resort to types of gages technically known as "slant tube differential" made partly of glass and angularly disposed.

Apart from wholly dispensing with gages of this type and employing simple types of dials having pointers operating after the general manner of the pointers or index fingers of steam gages, I eliminate glass from my construction and resort wholly to metal with the result of making a more serviceable and durable device and one moreover which may be easily understood by the average boilerman.

The object of my present invention, generally expressed, is to devise a draft gage in which independent readings are obtained by means of independent but concentrated pressure regulators so that, for example, when the device is used with a furnace, the engineer will have visibly indicated the pressure of the draft for primary combustion, the pressure in the combustion chamber above the grate, and the pressure of the gases at the outlet of the furnace, the readings being preferably arranged in superposition and as indicative of the order of their occurrence in the furnace, so that the engineer can readily determine at a glance the

exact condition of the gases in the furnace and thus be enabled to operate the furnace at a maximum degree of efficiency.

In the practical making up of my gage, the different readings or graduations are disposed in succession or consecutive assemblage within a single, compact, confining case, and preferably so arranged that the lower reading of the assemblage will correspond to and indicate the first change which takes place in the gases, such, for example, as the variation in pressure of the air entering beneath the grate for primary combustion,—then, that the reading above the lower reading, or that in the present instance which is the middle reading of the gage, will indicate the second change which takes place in the gases or the pressure of the gases in the combustion chamber,—and, lastly, that the third or uppermost reading will indicate the last change or that which means the variation in pressure at the outlet of the furnace,—with the result; as already mentioned, that the engineer can see at a glance the exact variations which have taken place in the gases as they pass through the furnace.

By this preferred arrangement it will be quite obvious that the gages will indicate step by step, so to speak, but at a single glance the course of the gas through the furnace in such a way that an unskilled furnace man cannot misunderstand it.

With the foregoing objects in view, my invention comprehends a gage, typical embodiments of which are represented in the accompanying drawings and hereinafter described, the particular subject-matter which I claim as novel being definitely specified in the claims.

In order to illustrate my invention, I have in the drawings shown two embodiments of it which are at present preferred by me, because in practice they will give satisfactory and reliable results. It is to be understood, however, that the various components in which my invention is shown as embodied can be modified in both arrangement and organization and that my invention is not therefore limited to the precise arrangement and organization shown in the drawings and hereinafter described.

In the accompanying drawings:—
Figure 1 represents in perspective a differential gage for a boiler-unit embodying

my invention, indicating a convenient arrangement of dials, the upper of which indicates the damper draft, the middle the draft of the combustion chamber, and the lower the forced draft.

Fig. 2 represents in front elevation, with the face plate of the gage-casing removed, the gage of Fig. 1, the view indicating an embodiment in which three sets of dia-

10 phragms are interposed between the inlets and the pointers of the three dials.

Fig. 3 represents a vertical, side, sectional elevation through Fig. 2 on the dotted line 3—3 of said Fig. 2.

15 Fig. 4 represents a view similar to that of Fig. 2, except that but two diaphragms are used, one in connection with the upper dial, the other in connection with the lower, while in connection with the intermediate dial or

20 that of the combustion chamber, I have illustrated a liquid seal invented by me and of the character set forth in an application for patent executed by me on the 6th day of March, 1917.

25 Fig. 5 is a vertical section on line 5—5 of Fig. 4.

Similar numerals of reference indicate corresponding parts.

Referring to the drawings:

30 1 designates a hollow casing preferably of sheet metal and of quadrangular form. The construction of the casing as such from a mechanical viewpoint is immaterial but the drawings show a convenient shape of

35 it and mode of putting it together, detailed explanation of which is unnecessary. The

back of the casing is designated 1^x, and in its front or face plate 2 are introduced three

40 dial windows one above the other, of glass or other transparent material, which are

designated respectively 4^x, 6^x and 8^x and which stand in front of and expose to view

45 dials respectively designated 4, 6 and 8, which are mounted in superposition, that is

to say one above the other, but slightly sepa-

50 rated from each other upon a pair of carrying brackets 2^x connected with the back 1^x of the casing.

Each dial is provided with the usual scale,—5 being that of the damper dial 4,—7 that of the combustion dial 6,—and 9 that of the forced draft dial 8.

55 Operating in connection with each of the dials is a pointer,—10 designating the pointer of the damper dial 4,—11 the pointer of the combustion dial 6,—and 12 the pointer of the forced draft dial 8.

The pointers, as will be understood by reference to Figs. 3 and 5, are each so bent as 60 to have their pointing ends between the casing windows and the dials. This formation is a matter of convenience of construction merely, but it enables me properly to dispose of them with relation to both the dials

65 and the diaphragms.

The swing or oscillation of these pointers is such as is usual in gages of the general character of steam gages, and the movement of each pointer is due to the pressure which enters the regulator through the inlets which are respectively connected with the main draft conduit of the furnace, the combustion chamber and the damper outlet. The furnace which is of any preferred character is not illustrated.

75 Thus, in the present instance, I have designated the inlet or conduit which is connected with the furnace outlet or damper draft and the pointer 10, as 13,—the inlet or conduit which is connected with the combustion chamber and the pointer 11, as 14,—and the inlet or conduit which is connected with the furnace main draft conduit of the furnace and the pointer 12, as 15.

75 In the construction of Figs. 2 and 3, there are interposed between the respective inlets and the pointers, flexible box or bellows dia-

phragms, so called, which under the pres-

80 sure of the gases admitted to them through

the respective inlets, expand or contract so

85 as, each, to raise or lower a lifting rod which is connected with a balanced shaft upon

90 which a pointer is mounted.

95 Any desired character of diaphragm; or equivalent device, may be resorted to. I prefer, however, to utilize such a bellows

diaphragm as is patented to John F. Sim-

mance and Jacques Abady, in and by Let-

ters Patent, No. 1,064,555, dated June 10th,

100 1913.

It might furthermore be here explained that in the construction shown in Figs. 4 and 5, I have employed but two bellows diaphragms, one connected with the damper draft pointer and the other with the forced draft pointer,—while in connection with the combustion chamber draft pointer I have used a liquid seal invented by me and of the character set forth in an application for patent executed by me upon the sixth day of March, 1917, which is constructed upon the same principle as a chemical balance and the sensibility of which can be com-

pared to that of such a balance.

The mounting of the pointers is prefer-

ably the following,—and as they are the same, a description of the mounting of one will serve for all.

Selecting the forced draft pointer 12,—19 designates a pair of standards erected 120 from the bottom of the casing and fixedly secured thereto.

Between the standards is pivotally mounted an oscillatory balance shaft 20, upon which is fixed a hub 21 of the pointer 125 12, so that as the pointer is fixed to its hub it will oscillate with the shaft.

22 is a balance weight depending from the hub of the pointer and fixed thereto. 23 is what I term a diaphragm balance, the 130

same being a balance weight carried by an arm 24 fixed to the balanced shaft and extending beyond said shaft away from the balance 23 and connected by a link 25 to a lifting rod 26 the lower end of which is connected with the diaphragm.

The balanced shaft 20 is at one end pivoted at 27 to the inner end of a bell-crank-lever 28, fulcrumed at 29 to one of the standards 19, which lever at its other end is connected with an adjusting bolt 30 the outer end of which extends beyond the casing and is provided with an adjusting thumb-knob 31 for altering the tilt of the lever 28 to set the pointer to zero.

It will now be apparent that I have devised a novel and useful differential gage which in practice will effectuate the objects that I have referred to as desirable, and that although I have shown and described 20 embodiments of it which will give satisfactory results, I do not confine myself to these embodiments as they are susceptible of modification in various particulars without departing from the spirit or scope of the invention or sacrificing any of its advantages.

Having thus described my invention, what I claim as new and desire to secure 30 by Letters Patent, is:—

1. In a draft gage,—an inclosing casing,—a plurality of dial windows disposed one above the other in the front face of the casing,—a corresponding plurality of dials 35 visible through said windows,—a plurality of pointers corresponding and operative with respect to the dials,—a corresponding plurality of pointer-actuating mechanisms,—and a corresponding plurality of 40 furnace-connecting pipes, said dials being

arranged one above the other in the same order as the flow of gases of which the pressures are to be measured.

2. In a draft gage,—an inclosing casing,—a plurality of dial windows disposed 45 one above the other in the front face of the casing,—a corresponding plurality of dials visible through said windows,—a plurality of pointers corresponding and operative with respect to the dials,—a corresponding 50 plurality of pointer-actuating mechanisms supported from the back of the casing,—and a corresponding plurality of furnace-connecting pipes, said dials being arranged one above the other in the same order as 55 the flow of gases of which the pressures are to be measured.

3. In a draft gage,—an inclosing casing,—a plurality of dial windows disposed 60 one above the other in the front face of the casing,—a corresponding plurality of dials visible through said windows,—a plurality of pointers corresponding and operative with respect to the dials,—a corresponding 65 plurality of pointer-actuating mechanisms supported from the back of the casing,—and a corresponding plurality of furnace-connecting pipes which enter the casing below the dials, said dials being arranged one above the other in the same order 70 as the flow of gases of which the pressures are to be measured.

In testimony whereof I have hereunto signed my name this 12th day of December, 1917.

ABRAM T. BALDWIN.
